(57) **CLAIM**

The ornamental design for a kitchenware rack base, as shown and described.

DESCRIPTION

FIG. 1 is a top perspective view of a kitchenware rack base showing my new design;

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a top perspective view of the kitchenware rack base shown in an environment of use; and,

FIG. 10 is a bottom perspective view of the kitchenware rack base shown in an environment of use.

The broken lines in FIGS. 9-10 showing kitchenware dividers represent environment and form no part of the claimed design. All other broken lines show portions of the kitchenware rack base that form no part of the claimed design.
